UNITED STATES PATENT OFFICE.

JOHN ALBERT SWINDELL, OF PITTSBURGH, PENNSYLVANIA.

ANNEALING-FURNACE.

1,112,236.

Specification of Letters Patent.

Patented Sept. 29, 1914.

Application filed December 12, 1913. Serial No. 806,224.

To all whom it may concern:

Be it known that I, JOHN ALBERT SWINDELL, a citizen of the United States, residing at Pittsburgh, in the county of Allegheny and State of Pennsylvania, have invented a new and useful Improvement in Annealing-Furnaces, of which the following is a full, clear, and exact description, reference being had to the accompanying drawings, forming part of this specification, in which—

Figure 1 is a transverse vertical section of one form of annealing furnace embodying my invention. Fig. 2 is a section on the irregular line II—II of Fig. 1. Figs. 3 and 4 are vertical sections showing two other forms of the invention. Fig. 4^a is a detail sectional view showing another form. Fig. 5 is a sectional perspective view showing still another form. Fig. 6 is a vertical section showing a fifth form of my invention. Fig. 7 is a section on the irregular line VII—VII of Fig. 6, and Fig. 8 is a view similar to Fig. 7 showing a still further modification.

My invention has relation to annealing furnaces and more particularly to furnaces of the class which are designed to receive and impart heat to annealing boxes containing sheets, plates or other articles which are to be annealed.

The invention is especially designed as an improvement upon the furnace described and claimed in the patent to William A. and J. C. Swindell, No. 624,401 of May 2, 1899. The furnaces of that patent have been highly successful in practical operation and have gone into wide use, particularly in the art of annealing sheets and plates.

The present invention is designed to still further increase the efficiency of the furnaces of the said patent.

With this object in view the invention consists mainly in the re-arrangement of the gas, air and waste ports of the furnace in such a manner that the products of combustion enter the annealing chamber of the furnace at its central portion (or in the case of a divided furnace, adjacent to the inner wall of each annealing compartment); and thence pass upwardly in parallel over the annealing boxes and thence downwardly through escape ports adjacent to the outer side walls of the annealing chamber or compartment. These outer side walls, being directly exposed to the atmosphere are subject to loss of heat and there is, therefore, a tend-

ency for the outer portions of the boxes to be at a somewhat lower temperature than the inner portions.

By my invention, the products of combustion, which are still at a high temperature, are continually impinged directly against these outer walls, thereby maintaining them at a high temperature.

The invention further consists in so arranging the air, gas and waste flues as to retain the advantages possessed by the furnaces of the said patent.

I also provide simple and efficient means for regulating the temperature of different portions of the furnace by the admission of relatively cold air from the outside, but in such a manner as to avoid undue cooling down of the annealing chamber or compartment.

In the accompanying drawings I have illustrated several different constructions of furnaces embodying my invention.

Referring first to that form shown in Figs. 1 and 2, the numeral 2 designates the side walls of the furnace, 3 the roof and 4 the base. 5 designates the annealing chamber, which is of double form, being designed to support a row of annealing boxes placed end to end at each side of the center. The furnace is provided with the usual charging doors 6 at one end.

The numeral 7 designates two gas inlet flues, one at each side of the central dividing wall 8 and these flues enter the furnace at one end and extend in a parallel longitudinal direction. Each of these flues has at its upper portion a series of ports 9 leading upwardly at opposite sides of the central wall 8. This wall 8 is preferably extended upwardly somewhat above the level of the box supporting portions 10 of the floor of the chamber 5, and may, if desired, be extended to any distance even entirely to the roof, thus dividing said chamber into two compartments, as indicated in full lines in Fig. 3. The outer walls 11 of the ports 9 are also preferably extended upwardly so as to direct the products of combustion upwardly into the annealing chamber.

12 designates the air inlet flues, one at each side of the furnace, and each of them having a plurality of ports 13 leading from their upper portion and communicating with the gas ports 9. The waste flues of the furnace each have two passes 14 and 14^a. The passes 14 are at the sides and communi-

cate with the annealing chamber 5 by means of a plurality of vertical ports 15 through which the waste gases descend at opposite sides of the said chamber. The passes 14^a of these waste flues are located at each side intermediate the adjacent air and gas flues, the two passes being connected at 14^b.

16 designates damper bricks which are adapted to extend through openings in the 10 side walls 2 of the furnace a short distance below the upper ends of the ports 15. These damper bricks are arranged to fit somewhat loosely in these openings and can be adjusted therein so as to regulate the draft. They 15 provide means by their effect upon the draft whereby the heat at different portions along the length of the annealing chamber can be regulated as may be desired. Any cold air admitted to these points does not directly 20 enter the annealing chamber, but passes down into the waste flues, and therefore does not chill the temperature in said chamber.

It will be noted that all the flues extend 25 in parallel longitudinal relation, being similar in this respect to the furnace of the Swindell patent above referred to. This is a feature of very great importance in practice, since the dividing walls between the 30 several flues are also longitudinally arranged and are thus much less liable to injury in the operation of the furnace. That is to say, these walls extend in the same direction as the movement of the boxes into 35 and out of the furnace. These boxes and their contents are of great weight and the total load on the furnace floor is frequently very large. This parallel longitudinal arrangement of these dividing walls provides 40 a supporting base of maximum strength. In these figures I have shown the inlets 12^a for the longitudinal air flues 12 as communicating with said flues centrally of their length, the air spreading and flowing longitudinally 45 in both directions and thence through the ports 13. It will also be noted that by the arrangement of flues described, I obtain the advantages of preheating the air, which is a feature of the said Swindell patent. These 50 furnaces are kept in a highly heated condition for relatively long periods. The entire base of the furnace, therefore, becomes very highly heated, not only by conduction through the floor of the annealing chamber, 55 but also by conduction through the walls separating the waste flues from the air and gas flues. The result is that both the air and gas are preheated to a very considerable degree before reaching the points of combustion. 60 This effects a considerable saving in fuel and utilizes heat which would otherwise be lost either by conduction through the base of the furnace into the foundation or by passing off through the stack. I have found 65 that this preheating, through the walls of

the waste flues, will take place to a beneficial extent even where these walls are of very considerable thickness owing to the high degree to which the furnace becomes heated in operation.

70 In the modification shown in Fig. 3, the construction is substantially the same as that just described, but the waste flues 17 are single pass flues instead of double pass.

75 In the modification shown in Fig. 4, the construction is the same as that shown in Fig. 3, except that instead of a single pass air flue at each side, I provide each air flue with double passes 18 and 19. This effects 80 a further preheating of the air. This form also differs from Fig. 3 in having a single central gas flue 20 which communicates with the air ports 21 from the air flues 19 by means of the vertical ports 22. In this form the central wall 8 is not present.

85 The construction illustrated in Fig. 4^a is similar to that shown in Fig. 4, but differs therefrom in that the ports 22^a are staggered, or alternate, with relation to the ports 21.

90 In the construction shown in Fig. 5, 23 and 23^a designate the double pass waste flues similar to those shown in Fig. 1. 24 designates the air flues and 25 the single central gas flue. Each air flue 24 has a series of 95 oblique transverse ports 26 leading from its upper portion into a chamber 27 formed by the hollow central wall 28. The gas flue 25 has two sets of vertical ports 29 and 30. The ports 29 lead upwardly at one portion of the wall 28, while the ports 30 lead upwardly at the opposite side of said wall, being shown in dotted lines in this figure. The gas and air ports are staggered so that at each side the gas and air ports alternate. 100 The gas escapes from the ports 29 at the upper edges of the baffle walls 31, while the air escapes adjacent to these points through openings 32 in the upper portion of the hollow wall 28.

110 In the form shown in Figs. 6 and 7, the waste flues 33 are single pass flues, while the air flues 34 and 34^a are double pass flues. 35 is a central gas flue. In this form the chamber 36 within the central hollow wall 115 37 forms an initial combustion chamber with which the passes 34^a of the air flues communicate by means of the ports 38 and with which the gas flue communicates by vertical ports 39. The products of combustion escape through the side openings 40 in said central wall. The construction shown in Fig. 8 is similar to that shown in Figs. 6 and 7, but instead of the air flues each making two complete passes, each air flue consists of an inlet portion 41 which extends to about the center of the furnace where it 120 communicates with the main air flue 42 from which the air flows in both directions.

125 The specific construction shown in Figs. 5, 130

6 and 7, are the joint invention of John C. Swindell and myself and form the subject matter of a co-pending joint application. These figures are illustrated and described 5 herein, however, as showing specific embodiments which the broader invention herein claimed may take.

It will be noted that all the forms of the invention described possess the advantages 10 of the longitudinal flue arrangement before described and also to a greater or less extent the advantages of air or air and gas preheating. In all the forms, the combustion originates at or near the central portion 15 of the furnace, and the products of combustion pass in opposite directions over the annealing boxes toward the outer side walls. The constructions provide for a high degree of uniformity in heating, not only as 20 to all the boxes, but as to different portions of the same box. The waste outlets being at the outer sides of the furnace not only maintain these side walls at a high temperature, but in chilling, action which the walls 25 would exert upon the gases is exerted upon outgoing waste gases after they have passed the boxes. It will also be noted that either side of the furnace can be worked to a large extent independently of the other side. It 30 frequently happens that a different character of material is being treated in one side of the furnace than in the other, and requiring either a different temperature, or treatment for a different length of time. In 35 furnaces constructed in accordance with my invention this can be readily done since the heat conditions at the two sides can be separately regulated.

The invention is subject to other modifications than those herein described without departing from the spirit and scope of the appended claims.

While my invention has been more specifically designed for use in annealing furnaces, it is obvious that it is applicable to other heating furnaces.

What I claim is:

1. A furnace of the character described, comprising a heating chamber or compartment for the articles to be heated, having an inlet port for the heating medium opening into the inner side of said chamber or compartment, and an outlet port for the waste gases leading from the outer side of 55 said chamber or compartment, the base of the furnace below said chamber or compartment having longitudinally arranged air, gas and waste flues, the waste flues having portions which are below the outer side portion 60 of the said chamber or compartment, and the gas flue being below the inner side of said chamber or compartment, the air and gas flues having ports which connect the flues with said inlet port, and the said outlet port being connected to the said waste flue, some of said flues having double passes in

outlet port being connected to the said waste 65 flue; substantially as described.

2. A furnace of the character described, having a heating chamber or compartment for the articles to be heated, said chamber having inlets extending along and opening 70 into its inner side portion, and also having outlets extending along and opening from its outer side portion, with a supporting floor for the articles to be heated between the said inlets and outlets, the base of the 75 furnace having longitudinally arranged air, gas and waste flues therein, with ports leading from the air and gas flues and communicating with said inlets, and other ports communicating with said outlets and leading to 80 the waste flue; substantially as described.

3. A furnace of the character described, comprising a heating chamber or compartment for the articles to be heated, having an inlet port for the heating medium opening 85 into the inner side of said chamber or compartment, and an outlet port for the waste gases leading from the outer side of said chamber or compartment, the base of the 90 furnace below said chamber or compartment having longitudinally arranged air, gas and waste flues, the waste flues having portions which are below the outer side portion of the said chamber or compartment, and the gas flue being below the inner side 95 of said chamber or compartment, the air and gas flues having ports which connect the flues with said inlet port, and the said outlet port being connected to the said waste flue, some of said flues having double passes; 100 substantially as described.

4. A furnace of the character described, comprising a heating chamber or compartment for the articles to be heated, having an inlet port for the heating medium opening 105 into the inner side of said chamber or compartment, and an outlet port for the waste gases leading from the outer side of said chamber or compartment, the base of the 110 furnace below said chamber or compartment having longitudinally arranged air, gas and waste flues, the waste flues having portions which are below the outer side portion of the said chamber or compartment, and the gas flue being below the inner side of said chamber or compartment, the air and gas flues having ports which connect the flues with 115 said inlet port, and the said outlet port being connected to the said waste flue, some of said flues having double passes in substantially 120 the same horizontal plane; substantially as described.

5. A furnace of the character described, comprising a heating chamber or compartment for the articles to be heated, having an inlet port for the heating medium opening 125 into the inner side of said chamber or compartment, and an outlet port for the

waste gases leading from the outer side of said chamber or compartment, the base of the furnace below said chamber or compartment having longitudinally arranged air, 5 gas and waste flues, the waste flues having portions which are below the outer side portion of the said chamber or compartment, and the gas flue being below the inner side of said chamber or compartment, the air and 10 gas flues having ports which connect the flues with said inlet port, and the said outlet port being connected to the said waste flue, together with damper means for the ports which connect the outlet with the waste 15 flues; substantially as described.

6. A furnace of the character described having an annealing chamber provided with waste port connections adjacent to its outer side walls, and with two sets of inlet port 20 connections adjacent its center, and also having means for supporting articles to be annealed at each side of the center between the inlet and outlet connections, the base of the furnace below said chamber having longitudinally arranged air and gas flues there- 25 in with which the said inlet port connections communicate, and also having a longitudinally arranged waste flue underneath each outer side portion of said chamber with which the waste port connections communi- 30 cate; substantially as described.

7. A furnace of the character described having its base provided with a longitudinally extending waste flue adjacent each of 35 its opposite sides, said flues having ports leading into the side portions of the annealing chamber of the furnace, and said furnace also having means whereby hot products of combustion are caused to pass from 40 the central portion of its annealing chamber toward the opposite side walls thereof, the base of the furnace having underneath its central portion a longitudinally extending gas flue, air supply and preheating 45 flues between the gas flue and each of the side waste flues, and port connections from said flues for bringing air and gas together at the central portion of the furnace; sub- stantially as described.

50 8. A furnace of the character described having its base formed with a longitudinal waste port adjacent each side thereof, said flues having ports leading upwardly at the side portions of the annealing chamber of 55 the furnace, and said ports having damper means, together with means for the introduction of the heating medium at the central portion of the furnace, the dampers providing means for independent regulation 60 of the draft at the two sides of the furnace; substantially as described.

9. A furnace of the character described having longitudinally extending substan-

tially parallel gas, air and waste flues within its base, the waste flues having portions 65 adjacent the side walls of the furnace and communicating with the side portions of the annealing chamber of the furnace, and the air flues having portions which are adjacent to the waste flues, the said gas and air 70 flues having port connections for bringing air and gas together at the central portion of the furnace and said chamber being arranged to permit of a transverse passage of the products of combustion across said 75 chamber from its central portion to the sides thereof throughout the major portion of its length; substantially as described.

10. A furnace of the character described, having a chamber to receive the material to 80 be heated, said chamber having inlet means for the heating medium at its central portion and opening directly into said chamber, outlet means for the products of combustion at each side portion of said chamber, said chamber having a supporting surface for the material to be heated between the outlet means at each side and the central inlet means, and being arranged to permit the products of combustion to flow 90 transversely across it from the center toward the side in both directions throughout the major portion of its length, and the base of the furnace below the chamber having longitudinally arranged gas and air flues 95 which are connected to the said inlet means, said base also having longitudinally arranged waste flues which are connected to the said outlets and which has portions which are adjacent to the side walls of the 100 furnace; substantially as described.

11. A furnace of the character described, having a chamber to receive the material to be heated, said chamber having inlet means for the heating medium at its central portion and opening directly into said chamber, outlet means for the products of combustion at each side portion of said chamber, said chamber having a supporting surface for the material to be heated between the outlet means at each side and the central inlet means, and being arranged to permit the products of combustion to flow 110 transversely across it from the center toward the side in both directions throughout the major portion of its length, the furnace also having means for supplying preheated air and gas to said inlet means, and having waste flues communicating with the said outlet means; substantially as described. 115

In testimony whereof, I have hereunto set my hand.

JOHN ALBERT SWINDELL.
